UNITED STATES PATENT OFFICE.

EUGENE E. AYRES, JR., OF SWARTHMORE, PENNSYLVANIA, ASSIGNOR TO THE B. A. S. COMPANY, OF PHILADELPHIA, PENNSYLVANIA, A CORPORATION OF DELAWARE.

CHLORINATION.

No Drawing.

Application filed February 4, 1927. Serial No. 165,876.

My invention relates to chlorination and particularly to bringing together in the vapor phase chlorine and a substance to be chlorinated in such manner that explosion is avoided.

In chlorination there is great danger of explosion when chlorine vapor is mixed with a hydrocarbon vapor in explosive proportions. When so mixed explosion will occur under the action of light or under the action of high heat or under the action of relatively low temperature if the pressure of the mixture is sufficiently high. Furthermore, a mixture having chlorine and hydrocarbon present in explosive proportions may be safely handled and safe reaction between the substances can be effected by merely heating such mixture in the absence of a flame or light that would initiate an explosion. It is therefore imperative to avoid ignition in any part of such a mixture. However, even though a mixture of chlorine and hydrocarbon is subject to such conditions of temperature and pressure that spontaneous explosion thereof is not likely to or will not occur, ignition may nevertheless occur at the point where the chlorine and hydrocarbon vapors are brought together, under those otherwise safe temperatures and pressures, to produce the mixture. Moreover, ignition may occur at the point where the chlorine and hydrocarbon are brought together even though the final mixture is not of explosive proportions under the existing temperature and pressure, although in such case explosion does not result from such ignition. In other words, ignition may occur at the point of junction regardless of whether the resulting mixture is of explosive proportions at the existing temperature and pressure. Also, there is little danger of ignition at the junction point when some substances are mixed with chlorine at atmospheric temperature but there is considerable danger of ignition at the junction point when the same substances are so mixed at higher temperatures. Pentane is an example of such a substance.

I have found that when hydrocarbons are to be mixed with chlorine in the vapor phase at a temperature at which the velocity of reaction between them is low, ignition at the junction point will not occur if that vapor into which the vapor is introduced is moving at sufficient velocity with respect to the junction point. For example, ignition will not occur if chlorine enters a stream of hydro-

carbon vapor that is moving at a velocity in excess of one-half of the velocity required for distinctly turbulent flow of the mixture, provided the vapors are brought together at a temperature at which the velocity of the reaction between them is low. This freedom from danger of ignition exists regardless of the proportions in which the chlorine and hydrocarbon are brought together and exist in the final mixture. Mixtures consisting of chlorine and hydrocarbon in explosive proportions can not be kept standing although the constituents of such mixtures may be safely brought together by the practice of my invention. An important feature of my discovery resides in the fact that in making mixtures of chlorine and hydrocarbon vapors explosion due to ignition at the junction point is avoided both where the final mixture is intended to contain chlorine and hydrocarbon in explosive proportion and when explosive mixtures are accidentally produced during the making of mixtures that are intended to be in non-explosive proportions.

The velocity at which the mixture will pass with turbulent flow through the conduit that carries it to the reactor, may be determined in various ways. A practical method of determining that velocity consists in cooling the exterior of the conduit as by circulation of water, placing a thermometer in the conduit with its bulb at the axis thereof, placing a second thermometer in the conduit with its bulb closely adjacent the wall of the conduit, increasing the velocity of flow until the two thermometers give substantially the same reading. So long as the flow is not rapid enough to produce turbulence the thermometer near the wall of the conduit will have a lower reading, but when the velocity of turbulent flow is reached the resulting agitation within the conduit will cause the two thermometers to have substantially the same reading.

When the chlorine is mixed with hydrocarbon by being introduced into the hydrocarbon vapor, ignition at the point of junction is avoided in the practice of my invention at temperatures at which ignition would otherwise occur even though, as is very apparent, mixtures of all proportions occur in the zone in which the substances come together and while they are becoming disseminated one within the other.

In the chlorination of substances on a com-

mercial scale, the chlorine vapor and the substance to be chlorinated are brought together and the resulting mixture is conducted to and introduced into a reactor in which the reaction is caused to occur at a rapid rate by conditions imposed upon the mixture in the reactor, as by the application of heat, the conditions being so maintained that a desired substitution of chlorine takes place instead of an ignition. If conditions are such that the mixture is delivered to the reactor without substantial chlorinating reaction in transit thereto the rate of reaction in the mixture passing to the reactor may be said to be low and practical handling of the mixture is possible without serious danger of ignition; and further references herein to a low rate of reaction are intended to refer to such a safe rate.

Thus, as a specific example of the application of my invention, it is possible to introduce chlorine into pentane vapor to produce a mixture of even equal proportions and having a temperature of 90° C. without the occurrence of ignition at the point of junction provided the stream of pentane is moving in excess of one-half of the velocity required for distinctly turbulent flow of the mixture, e. g., fifty feet per second, but ignition would occur at that temperature at the point of junction if the pentane were not moving with the necessary velocity even though the proportion of pentane to chlorine were as high as 5:1, and perhaps higher.

Conversely, if hydrocarbon vapor is introduced into a stream of chlorine vapor, the velocity of the chlorine vapor in respect to the point of junction must, in accordance with my invention, be maintained sufficiently high to prevent ignition. For example, if methane is passed into chlorine vapor in the preparation of carbon tetrachloride, ignition is prevented at ordinary temperatures when the velocity of the chlorine vapor is higher than fifty feet per second even though the ratio of chlorine to methane is as low as four to one. Ignition is likely to occur with this ratio when the velocity of the chlorine vapor becomes less than fifty feet per second. The velocity at which the vapor must be moving in order to prevent, in accordance with my invention, an ignition at the junction point, depends upon the ratio of chlorine to hydrocarbon and upon the temperature of the resulting mixture and that velocity must be increased as the temperature increases and as the proportions of the mixture approach the proportions of the most explosive mixture. I have found that the velocity of reaction between vapors of pentanes and chlorine vapor is very low at temperatures below 150° C.

In practice, however, it is advisable to maintain a higher velocity than is necessary for normal operation because accidental

variations of temperature and of proportions of the mixture might otherwise produce conditions requiring such higher velocity to certainly prevent ignition. The existence of a flame at the point where chlorine and the hydrocarbon mix causes explosion of explosive mixtures, or, if the mixture does not explode as a result of ignition, causes the production of products that are not desired, as described in Patent No. 1,286,353. In the practice of this invention the existence of such a flame is prevented by maintaining such conditions with respect to the velocity of the vapors at the time they are brought together that such a flame cannot exist or form.

A further feature of my invention is the chlorination of substances, and particularly saturated aliphatic hydrocarbons of three to six carbon atoms, by causing the initiation and completion of the chlorinating reaction to occur promptly after the chlorine and substance are brought into contact, and thereby preventing formation of some chloride before the mixture comes into the influence of the reacting agent (heat or light) and the consequent formation of undesirable higher chlorides after the mixture comes into the influence thereof.

What I claim and desire to secure by Letters Patent is:

1. In the chlorination of hydrocarbons that exist in vapor phase at temperatures at which their rate of reaction with chlorine is low, the step comprising introducing chlorine into the hydrocarbon vapor while maintaining the latter in motion at a velocity in excess of one-half of that required for distinct turbulent flow of the mixture.

2. In chlorination of hydrocarbons wherein chlorine is introduced into the hydrocarbon, the step comprising maintaining the vapor of a hydrocarbon, that exists in vapor phase at a temperature at which its rate of reaction with chlorine is low, in motion at a velocity sufficiently high to prevent persistence of ignition at the point of introduction of the chlorine under the temperature existing at that point.

3. In chlorination of hydrocarbons, the step comprising bringing together chlorine vapor and vapor of a hydrocarbon that exists in vapor phase at a temperature at which its rate of reaction with chlorine is low, by maintaining one of the vapors in motion at a sufficient velocity, with respect to the point at which the vapors are brought together, to prevent persistence of ignition of the mixture at that point at the existing temperature while introducing the other vapor into the vapor that is in motion.

4. In chlorination of hydrocarbons, the step comprising bringing together chlorine vapor and vapor of a hydrocarbon that exists in vapor phase at a temperature at which its rate of reaction is low, by maintaining one

of the vapors in motion at a velocity not less than fifty feet per second in a conduit not more than eight inches in diameter with respect to the point at which the vapors are brought together while introducing the other vapor into the vapor that is in motion.

5. In the chlorination of pentanes the step comprising introducing chlorine vapor into pentane vapor while maintaining the pentane vapor in motion at a sufficient velocity with respect to the point at which the chlorine is introduced to prevent persistence of ignition of the mixture at the existing temperature.

10 6. In the chlorination of pentanes the step comprising introducing chlorine vapor into pentane vapor while maintaining the pentane vapor in motion at a velocity in excess of fifty feet per second in a conduit not more than eight inches in diameter with respect to the point at which the chlorine is introduced.

15 7. In the chlorination of pentanes the step comprising introducing chlorine vapor into pentane vapor while maintaining the pentane vapor in motion at a sufficient velocity with respect to the point at which the chlorine is introduced to prevent persistence of ignition of the mixture while maintaining the temperature of the mixed vapors below

20 30 150° C.

8. In the chlorination of pentanes the step

comprising introducing chlorine vapor into pentane vapor while maintaining the pentane vapor in motion at a velocity in excess of fifty feet per second in a conduit not more than eight inches in diameter with respect to the point at which the chlorine is introduced while maintaining the temperature of the mixed vapors below 150° C.

35 9. In the chlorination of hydrocarbons, the step comprising bringing together chlorine vapor and vapor of a hydrocarbon that exists in vapor phase at a temperature at which its rate of reaction with chlorine is low, by maintaining one of the vapors in motion at a velocity in excess of one-half of that required for distinct turbulent flow thereof, with respect to the point at which the vapors are brought together, while introducing the other vapor into the vapor that is in motion.

40 45 50 10. In the chlorination of pentanes, the step comprising bringing together chlorine vapor and vapor of the pentanes, by maintaining one of the vapors in motion, with respect to the point at which the vapors are brought together, at a velocity in excess of one-half of that required for distinct turbulent flow thereof while introducing the other vapor into the vapor that is in motion.

55 In testimony whereof, I have signed my name to this specification.

EUGENE E. AYRES, JR.
